United States Patent Office.

CHARLES CHINNOCK, OF BROOKLYN, NEW YORK, ASSIGNOR TO
I. LITTLE HYDE, OF NEW YORK CITY.

Letters Patent No. 94,564, dated September 7, 1869; antedated August 27, 1869.

IMPROVEMENT IN OIL-CAN.

The Schedule referred to in these Letters Patent and making part of the same.

To all whom it may concern:

Be it known that I, CHARLES CHINNOCK, of Brooklyn, in the county of Kings, and State of New York, have invented a new and useful Improvement in Oil-Cans; and I do hereby declare that the following is a full, clear, and exact description of the same, reference being had to the accompanying drawing, forming a part of this specification, in which is represented a vertical section of an oil-can, constructed according to my improvement.

This invention relates to the construction of cans for oiling machinery, whereby a stream of oil may be thrown forcibly and with such precision that joints not easily accessible may be oiled with little or no waste of oil.

It consists, first, in a chamber in the upper part of the reservoir of the can, provided with an outlet through the nozzle above, and communicating with the reservoir by means of a tube below, which extends upward into the said chamber to a point near the top thereof, and terminates below into a flexible tube of sufficient length and degree of flexibility to extend to any part of the reservoir.

It consists, secondly, in a valve situated in the cap of the filling-nozzle, and so constructed as to open inwardly, and by means of which air is admitted into the reservoir to fill the vacuum caused by the consumption of the oil and by the springing out of the bottom of the can after it has been relieved from the external pressure by which it is pressed inward when oiling.

In order that others may be better enabled to understand the construction and operation of my improvement, I will proceed to describe it, with reference to the drawings.

A is a chamber in the upper part of the reservoir E, which terminates above into the nozzle a.

B is a tube, passing through and screwed into the lower extremity of the chamber A, extending above the centre of the chamber upward and reaching downward below the bottom of the chamber A, a sufficient distance to attach thereto a tube, B', of leather or other suitable flexible material, of sufficient length and degree of flexibility to reach any part of the reservoir E.

F is an outer shell or jacket encasing the nozzle-tube a, not only for the purpose of protecting the

same from injury, but, by its lower extremity being attached to the base of the nozzle a, a space or chamber, C, is formed, which receives the waste oil which runs down upon the outside of the nozzle after being used, and retains the same for further use upon such parts of the machinery as may be lubricated by inverting the can, thereby effecting a saving of oil which would otherwise be wasted.

D is the cap, which closes the filling-nozzle, into which is inserted a valve, e, constructed so as to open inward, and through which air is admitted to fill the vacuum occasioned by the consumption of the oil, and by the springing out of the bottom of the can after external pressure has been removed.

The operation of my invention is effected in the usual way by compression of the bottom of the can, which forces the oil up through the tube B into the chamber A, and out at the nozzle a, leaving the chamber A, after such operation, full of oil to the level of the tube B, and is there retained for oiling such joints or journals as are easy of access, and which may be lubricated by inverting the can, in which instance compression of the bottom is not necessary, as the chamber A is of a capacity to contain such a quantity of oil as is generally sufficient for this purpose, and hence will supply to the journal or joint a desirable quantity, and no more, thus obviating the objection to an ordinary oil-can, in which there is no means of regulating the quantity of oil discharged at a time, air being supplied to the chamber A, when the can is inverted, through the tubes B B', by the rarefaction or expansion of the air contained in the can sufficiently to allow the oil to flow therefrom.

What is here claimed, and desired to be secured by Letters Patent, is—

1. The chamber A, arranged in combination with the tubes B B', nozzle a, and reservoir E, of an oil-can, substantially as herein shown and described.

2. The combination of the valve e with the reservoir E, tube B B', and chamber A, substantially as and for the purpose specified.

CHAS. CHINNOCK.
